CLAIM

The ornamental design for a toilet seat lift, as shown and described.

DESCRIPTION

FIG. 1 is a perspective view of a toilet seat lift in an extended position;

FIG. 2 is a front view of a toilet seat lift in an extended position;

FIG. 3 is top view of a toilet seat lift in an extended position;

FIG. 4 is a bottom view of a toilet seat lift in an extended position;

FIG. 5 is a right side view of a toilet seat lift in an extended position;

FIG. 6 is a left side view of a toilet seat lift in an extended position;

FIG. 7 is a perspective view of a toilet seat lift in a down position with an arm in a rotated position;

FIG. 8 is a front view of a toilet seat lift in a down position with an arm in a rotated position;

FIG. 9 is top view of a toilet seat lift in a down position with an arm in a rotated position;

FIG. 10 is a bottom view of a toilet seat lift in a down position with an arm in a rotated position;

FIG. 11 is a right side view of a toilet seat lift in a down position with an arm in a rotated position;

FIG. 12 is a left side view of a toilet seat lift in a down position with an arm in a rotated position;

FIG. 13 is a perspective view of a toilet seat lift in a down position;

FIG. 14 is a front view of a toilet seat lift in a down position;

FIG. 15 is top view of a toilet seat lift in a down position;

FIG. 16 is a bottom view of a toilet seat lift in a down position;

FIG. 17 is a right side view of a toilet seat lift in a down position; and,

FIG. 18 is a left side view of a toilet seat lift in a down position.

The broken lines showing portions of the toilet seat lift form no part of the claimed design.
